US00D987218S

(12) **United States Design Patent** (10) **Patent No.:** **US D987,218 S**
Liu (45) **Date of Patent:** **** May 23, 2023**

(54) **VACUUM CLEANER**

(71) Applicant: **Shenzhen Shouzheng Chuqi Technology Co., Ltd.**, Shenzhen (CN)

(72) Inventor: **Shuangyin Liu**, Shenzhen (CN)

(**) Term: **15 Years**

(21) Appl. No.: **29/886,172**

(22) Filed: **Mar. 6, 2023**

(30) **Foreign Application Priority Data**

Dec. 2, 2022 (CN) 202230807384.3

(51) **LOC (14) Cl.** **30-10**

(52) **U.S. Cl.**

USPC **D32/18**; D30/158

(58) **Field of Classification Search**

(57) **CLAIM**

The ornamental design for a vacuum cleaner, as shown and described.

DESCRIPTION

FIG. 1 is a perspective view of a vacuum cleaner showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 2; and,

FIG. 11 is an enlarged view of portion 11 shown in FIG. 5. The dash-dot broken lines in the drawings depict portions of the vacuum cleaner that form no part of the claimed design.

The dot-dash broken lines represent boundaries of the enlarged portions and form no part of the claimed design.

1 Claim, 11 Drawing Sheets
